Patented Aug. 6, 1918.

Inventor,
Jeremiah G. McEneery
By James R. Offord
Atty.

UNITED STATES PATENT OFFICE.

JEREMIAH G. McENERY, OF CHICAGO, ILLINOIS.

LIQUID-DISPENSER.

1,274,915.

Specification of Letters Patent. Patented Aug. 6, 1918.

Application filed May 23, 1917. Serial No. 170,379.

To all whom it may concern:

Be it known that I, JEREMIAH G. McENERY, a citizen of the United States, and a resident of Chicago, in the county of Cook and State of Illinois, have invented certain new and useful Improvements in Liquid-Dispensers, of which the following is a specification.

My invention relates to an improved dispenser for liquids such as liquid soap.

My improved dispenser belongs to that class in which a spout plunger extends downwardly from the liquid reservoir and is provided with a dispensing passageway normally closed to the container contents but being brought into position to receive and dispense the contents when the plunger spout is forced upwardly. One of the important features of my invention is the provision of a plunger chamber which communicates with the liquid reservoir through a passageway which is of such capacity relative to that of the plunger passageway that only part of the chamber will contain liquid, air filling the remaining space to be compressed when the plunger is raised and to force liquid from the chamber into and through the plunger passageway, part of the air being also forced upwardly into the reservoir. Then when the plunger is suddenly returned as by a spring, the suction effect produced in the plunger chamber will cause air to be drawn upwardly through the plunger passageway and a fresh charge of liquid drawn into the plunger chamber. Another feature of the invention resides in means for adjusting, relative to the plunger passageway, the capacity of the passageway which connects the reservoir with the plunger chamber.

The above and other features of my invention are embodied in the structure shown on the accompanying drawings. In these drawings

Figure 1 is a vertical diametral view of the dispenser and a supporting bracket therefor, and

Fig. 2 is a plan view of the dispensing fitting.

The cylindrical cup 5 has interior threads for receiving the outlet neck 6 of the reservoir 7, and depending from the cup is the lug 8 having exterior threads for engaging in the threaded circular end 9 of the supporting bracket 10. The lug has the axial guide passageway 11 for the plunger spout

12, which a distance downwardly from its upper end has the annular abutment and supporting flange 13 whose under surface is preferably conical to fit the conical seat 14 surrounding the upper end of the passageway 11. A dispensing passageway or duct 15 extends downwardly through the plunger spout from the side inlet opening 16 to the lower end of the plunger, the top of the inlet 16 being just below the flange 13 to be closed when the plunger is down and to be open to the space above the seat 14 when the plunger is raised.

Within the cup 5 is the cylindrical frame or shell 17 closed at its upper end by the top 18 and open at its lower end, the outer diameter of the shell being such that it will readily pass through the neck 6 of the reservoir, and the inner diameter being such that the shell at its lower end will surround the annular boss 19 surrounding the seat 14 for the plunger. At its lower edge the frame 17 has the lateral annular flange 20 which seats on the bottom of the cup 5 within the raised annular seat 21 at the lower corner of the cup 5. Engaging the top of the flange 20 and seat 21 is a washer 22 of rubber or other material which, when the reservoir 7 is screwed into the cup, is compressed to seal the chamber *c* in the frame 17 from the cup 5 and the reservoir, the only communication between the reservoir and the chamber *c* being through the passageway 23 in the top 18 of the frame. At its inner side the top 18 has the annular pocket 24 for seating the upper end of a compression spring 25 which at its lower end surrounds the top of the plunger 12 and seats against the flange 13.

In accordance with my invention the capacity of the passageway 23 has a fixed relation to the capacity of the plunger passageway 15, the passageway 23 being preferably smaller, and means are preferably provided for adjusting the size of the passageway 23. As shown in Fig. 2, this passageway may be in the form of a slot over which a plate 26 is pivoted to be shifted to adjust the available passageway through the slot between the reservoir and the chamber *c*.

The operation is now apparent. When the device is empty the reservoir and the chamber *c* will be filled with air, and when liquid is charged into the reservoir some will flow through the passageway 23 into chamber *c*, but this chamber will not be filled as on account of the small capacity of the passage-

way 23 air will be entrapped in the chamber. Then when the plunger spout is pushed upwardly and the volume of the chamber reduced, the air above the liquid in the chamber will be compressed and will force the liquid into and through the passageway 15 to be discharged. Some of the air is also forced upwardly through the passageway 23 into the reservoir. When the plunger spout 10 is released the spring 25 will throw it back to its lower position. During such return movement of the plunger the volume of the chamber *c* is increased and suction effect is produced therein, and this will cause air to 15 be drawn into the chamber through the plunger passageway 15, and will also cause liquid to be drawn into the chamber from the reservoir through the passageway 23. The proportion of air and liquid in the 20 chamber *c* after a dispensing operation depends upon the relative capacities of the passageways 15 and 23. The smaller the passageway 23, the greater will be the proportion of air drawn into chamber *c*, while 25 if the passageway 23 is made greater, less air and more liquid will be drawn into the chamber during return of the plunger. By means of the plate 26 the area of the passageway 23 relative to that of the spout passageway can be adjusted, and for each adjustment there will be only a predetermined 30 quantity of liquid in the chamber *c* available to be dispensed when the plunger is raised and depending upon the degree of raising of the plunger a proportionate amount of this 35 liquid in chamber *c* will be dispensed. An important and very desirable result of the above construction and operation is that during each up-stroke of the plunger the 40 passageway 23 will be cleaned by the air forced therethrough, and during each return movement of the plunger its passageway 15 is thoroughly cleaned by the air sucked upwardly therethrough. After each 45 dispensing operation the plunger duct 15 is entirely clear of liquid and dripping and clogging is entirely eliminated.

To prevent closure of the lower end of passageway 15 when the plunger is raised by 50 the hand, side outlets 27 and 28 may be provided with their outlet ends sufficiently elevated to prevent closure by the hand.

In the bottom of cup 5 annular clearance 55 pockets 29 may be provided for receiving solid particles in the liquid which might otherwise prevent accurate seating and sealing of the frame 17.

The liquid receptacle 7 is preferably of glass and may be permanently closed at the 60 top and filled by removing it from the cup 5. However, I prefer to provide the inlet neck 30 at the top to be closed by a cap 31 provided with a disk or washer 32.

I do not desire to be limited to the exact 65 construction, arrangement and operation

shown and described as modifications are no doubt possible which would still come within the scope of the invention. I claim as follows:

1. In a liquid dispenser, the combination 70 of a liquid reservoir having an opening in its lower end, a supporting base for supporting said reservoir, said base having a guide passageway, a dispensing plunger slidable vertically in said passageway, a dispensing duct through said plunger closed by said base when said plunger is down, a casing open at its lower end and seating on said base around the upper end of said plunger, the top of said casing being closed 75 and provided only with a small orifice for connecting the chamber within said casing with the interior of the reservoir, a spring tending to hold said plunger down, said plunger passageway being brought into 80 communication with said chamber when the plunger is raised, said orifice being sufficiently small to prevent filling of said chamber with liquid when the plunger is down whereby the air in said chamber above 85 the liquid therein will be compressed during upward movement of the plunger to force the liquid in said chamber downwardly through the plunger passageway.

2. In a dispensing device of the class described, the combination of a supporting base, a guide passageway therethrough, a dispensing plunger shifting vertically in said passageway and adapted to close the same when it is down, a dispensing passageway through said plunger closed at its upper end by said base when the plunger is down, a receptacle mounted on said base and having an opening surrounding said plunger, a casing secured on said base above the plunger and plunger passageway and forming a chamber, the top of said casing having a restricted passageway for connecting said chamber with the reservoir and for preventing escape of all the air in said 100 chamber when the reservoir is filled, a spring tending to hold the plunger down, upward movement of the plunger bringing its dispensing passageway into communication with said chamber and causing compression of the air in said chamber to force liquid from said chamber through said dispensing passageway, return of the plunger to its lower position causing suction effect in said chamber to draw air thereinto 110 through the dispensing passageway and liquid thereinto through said restricted orifice.

3. In a dispensing device of the class described, the combination of a supporting 125 base, a vertical guide passageway therethrough, a plunger filling said passageway but slidable therein, said plunger having a dispensing duct therethrough closed at its upper end by said base when the plunger is 130

- down, a liquid reservoir mounted on said base and surrounding the upper end of the plunger, a casing mounted on said base over the plunger end and extending into said 5 reservoir opening, said casing forming a chamber into which the plunger may pass when shifted upwardly, a spring resisting upward movement of the plunger, and a communicating passageway for connecting 10 the top of said chamber with said reservoir, said communicating passageway being restricted to prevent complete filling of said chamber with liquid whereby when said plunger is raised the air entrapped in said 15 chamber will be compressed and liquid discharged from said chamber into and through said dispensing duct.
4. In a dispensing device of the class described, the combination of a supporting 20 base, a vertical guide passageway therethrough, a plunger filling said passageway but slideable therein, said plunger having a dispensing duct therethrough closed at its 25 upper end by said base when the plunger is down, a liquid reservoir mounted on said base and surrounding the upper end of the plunger, a casing mounted on said base over the plunger end and extending into said 30 reservoir opening, said casing forming a chamber into which the plunger may pass when shifted upwardly, a spring resisting upward movement of the plunger, said dispensing duct being brought into communication with said chamber when the plunger is 35 raised, a communicating passageway for connecting the upper end of said chamber with said reservoir, said communicating passageway being sufficiently restricted to cause the entrapping of air in said chamber,
- upward movement of the plunger causing 40 compression of the entrapped air and forcing thereby of the liquid in said chamber through the dispensing duct and discharge of air through the communicating passageway into the reservoir, return of said 45 plunger to its lower position causing suction effect in said chamber whereby air and liquid are drawn into said chamber through the dispensing duct and communicating 50 passageway respectively.
5. In a liquid dispensing device of the class described, the combination of a supporting base having a vertical guide passageway therethrough, a dispensing plunger filling said passageway but slideable therein, 55 said plunger having a dispensing duct closed at its upper end by said base when said plunger is down, a liquid reservoir mounted on said base and having an opening, a casing on said base over the top of the plunger 60 and extending into said reservoir opening, said frame forming a chamber into which the plunger may be raised to bring the dispensing duct into communication with the chamber, and a communicating passageway 65 connecting the top of said chamber with the reservoir, said communicating passageway being of such capacity relative to that of the dispensing duct that when said plunger is raised and its passageway connected with 70 said chamber part of the contents of said chamber will flow through the dispensing duct and part through said communicating passageway.

In witness whereof I have hereunto subscribed my name this 21st day of May, A. D. 75
1917.

JEREMIAH G. McENERY.
